UNITED STATES PATENT OFFICE.

JAMES L. ERSKINE, OF NEW YORK, N. Y.

DESIGN FOR A SHAVING-BRUSH.

No. 39,899.

Specification for Design.

Patented March 30, 1909.

Application filed January 23, 1909. Serial No. 473,944. Term of patent 7 years.

To all whom it may concern:

Be it known that I, JAMES L. ERSKINE, a citizen of the United States, residing in the city of New York, borough of Brooklyn, in the county of Kings and State of New York, have invented a new, original, and ornamental Design for a Shaving-Brush, of which the following is a specification, reference being had to the accompanying drawing, forming part thereof.

The figure is a perspective view of a shaving brush showing my design.

I claim:

The ornamental design for a shaving brush, as shown.

JAMES L. ERSKINE.
